(57) **CLAIM**

The ornamental design for door closer case with a removable panel, as shown and described.

DESCRIPTION

FIG. 1 is a perspective view of a door closer case with a removable panel showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded perspective view thereof, showing the top panel separated from the door closer case; and,

FIG. 9 is a perspective view thereof, showing the panel partially pulled out from a door closer case.
